CLAIM

The ornamental design for a combined portfolio and writing pad, substantially as shown and described.

DESCRIPTION

FIG. 1 is a perspective view of a combined portfolio and writing pad showing our new design in a partially open condition;

FIG. 2 is a perspective view thereof with the writing pad removed from the pocket;

FIG. 3 is a front perspective view thereof in the fully open condition; and

FIG. 4 is a rear perspective view thereof.

FIG. 1

FIG. 3

FIG. 2

FIG. 4

UNITED STATES PATENT OFFICE
CERTIFICATE OF CORRECTION

Patent No. Des. 267,653 Dated January 18, 1983

Inventor(s) Ronald A. Miller and Robert Korstanje

It is certified that error appears in the above-identified patent and that said Letters Patent are hereby corrected as shown below:

On the title page after Item /57/ should read:

-- Be it known that we, Ronald A. Miller and Robert Korstanje have invented a new, original, and ornamental design for a combined portfolio and writing pad, of which the following is a specification, reference being had to the accompanying drawing, forming a part hereof. --.
